ASPARAGUS BASKET

Fred H. All, Allendale, S. C.

Application September 13, 1937, Serial No. 163,706

4 Claims. (Cl. 146—1)

This invention relates to baskets, and its general object is to provide a basket that is primarily designed for handling and initially bunching asparagus and the like, it being especially adapted for use by the cutter in the field, in that the sprigs or tips can be easily and expeditiously placed in the basket after being cut without material danger of damage or breakage thereto, and the basket is shaped to automatically bunch or to hold the sprigs in bundle formation, so as to allow easy cutting thereof to the proper length, when the basket is full, with the result, that butts, stems and waste matter can be left in the field, and thence the sprigs are ready for the grading or packing shed, when brought from the field.

A further object is to provide an asparagus basket that is light in weight, easy to handle and carry, simple in construction, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a perspective view of the basket which forms the subject matter of the present invention.

Figure 2 is a front view thereof.

Figure 3 is a sectional view taken approximately on line 3—3 of Figure 2, looking in the direction of the arrows.

Figure 4 is a sectional view taken approximately on line 4—4 of Figure 3 looking in the direction of the arrows.

Referring to the drawing in detail, it will be noted that my basket includes two spaced sections which are referred to as a body section and an end section, and each section includes a pair of wall members indicated respectively by the reference numerals 1, 2, 3 and 4, the wall members 1 and 2 being for the body section and the wall members 3 and 4 for the end section.

A base frame aids in holding the wall members in proper position, and in a manner whereby the wall members 1 and 2 are inclined rearwardly, and the wall members 3 and 4 are disposed in an upright vertical position, as best shown in Figure 1. The base frame includes side strips 5 and strips 6, the latter being disposed at the front

end of the basket and the strips are nailed or otherwise secured to the wall members. The wall members are likewise provided with inclined braces 7 and 8 extending diagonally between the same and secured thereto, by nails or other means. The wall members are reenforced by transverse strips 9 secured to the confronting faces thereof adjacent to the lower ends, as clearly shown in Figures 1 and 3.

Each wall member is cut away to provide an opening and the openings extend from adjacent the lower ends of the wall members and through the upper ends thereof. It will be noted from Figure 2, that the openings are substantially semi-circular in formation and slightly elongated, with the greatest degree of curvature at the lower portions thereof. The openings of the wall members are indicated by the reference number 10, and each opening is beveled downwardly from the front to the rear of the basket.

Mounted in the openings of the wall members 1 and 2 and secured thereto in the manner to follow the shape thereof is a sheet 11 of reticulated material such as wire mesh, and the sheet 11 bridges the wall members 1 and 2 to provide a closure including curved sides and bottom. Bridging the openings of the wall members 3 and 4, is a like sheet 12 of reticulated material to provide curved sides and bottom, and it will be noted as best shown in Figure 3, that the lower portions of the openings 10 extend one below the other in step formation from the front end of the basket, so that the bottoms of the closures provided by the sheets 11 and 12 are inclined rearwardly.

The rear end of the basket is closed by a solid wall or back 13 which extends above the wall member 1, and is secured thereto. The front end of the basket is open and it will be obvious that the sprigs of the asparagus and the like are cut in the usual manner and placed in the basket, with the tip ends innermost, so that wall 13 provides an abutment means therefor.

I also provide a handle for the basket, the handle being of the bail type and indicated by the numerical reference 14 and has its ends reenforced by collar members 15. The collared ends of the handle are pivotally secured to the upper longitudinal strips 16 of the body section adjacent to the inner ends thereof, through the instrumentality of pivot pins 17. The end section is likewise provided with upper strips 18 and the strips 16 and 18 are secured to the wall members, as best shown in Figures 1 and 4. The strips 16 and 18 are arranged in engaged pairs as best

shown in Figure 4, and the upper edges of the sheets 11 and 12 may be secured between the pairs of strips, but in any event the upper edges of the sheets 11 and 12 are fixed, and as shown in Figure 4 are secured to the innermost strips.

It will be noted, as best shown in Figure 1, that the end section is spaced at a considerable distance from the body section to provide between the same, a knife receiving space. When the basket is filled with sprigs, they bridge the space and the butt ends of the sprigs are cut along the inclined wall member of the body section, so that all the sprigs will be of equal length. It will, of course, be understood that the tip ends of the sprigs are disposed in abutting relation with the front wall 13. When the sprigs are cut, the portion remaining within the end section and which are called butts, can be removed from the basket with the result the butts, stems and waste matter can be left in the field, thence the tips of the sprigs which remain in the body section are ready for the grading and packing shed, and can be carried by my basket from the field or transferred from the basket to a carrying crate in the field in bundles and carried to the packing shed in said carrying crate, without fear of bruising, damaging or breaking the same.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A basket designed for handling asparagus tips and the like, and comprising a body section, an end section spaced from the body section to provide a knife receiving space between the sections, said sections having open upper portions, said end section having open ends, said body section having an open inner end and a closed outer end, the latter providing the rear of the basket, and each section having a rounded bottom inclined downwardly from the front to the rear ends of the basket.

2. A basket designed for handling asparagus tips and the like, and comprising a body section,

an end section spaced from the body section to provide a knife receiving space between the sections, reticulating material providing the sides and bottoms of the sections and each section having an open upper portion, said end section having open ends, said body section having an open inner end and a closed outer end, the latter providing the rear of the basket, and the bottoms being curved transversely and inclined downwardly from the front to the rear ends of the basket.

3. A basket designed for handling asparagus tips and the like, and comprising a base frame, a body section, an end section spaced from the body section to provide a knife receiving space between the sections, said sections secured to and rising from the base frame, reticulated material included in each section and providing the sides and bottoms therefor, said sections having open upper portions, said end section having open ends, said body section having an open inner end and a closed outer end, the latter providing the rear of the basket, the bottoms being rounded and inclined downwardly from the front to the rear ends of the basket, and a handle for the basket and pivotally secured to the body section.

4. A basket designed for handling asparagus tips and the like, and comprising a base frame, a body section, an end section spaced from the body section to provide a knife receiving space between the sections, a pair of wall members included in each section and having substantially semi-circular openings therein extending through the upper ends thereof, said wall members being secured to and rising from the base frame, sheets of reticulated material bridging the wall of each section and having their ends secured to the walls of the openings, the walls of the openings being inclined from the front to the rear ends of the basket for disposing the bottoms of the sections accordingly, the end section having open ends and the outer end thereof providing the front of the basket, the body section having an open inner end, a solid wall closing the outer end of the body section, reinforcing and bracing means for the sections, and a handle for the basket and pivotally secured to the body section.

FRED H. ALL.
